UNITED STATES PATENT OFFICE.

STANISLAW KIELAR, OF MILWAUKEE, WISCONSIN.

DESIGN FOR A ROLLING-PIN.

51,070.

Specification for Design.

Patented July 24, 1917.

Application filed May 16, 1917. Serial No. 169,137. Term of patent 7 years.

To all whom it may concern:

Be it known that I, STANISLAW KIELAR, a citizen of the United States, residing at Milwaukee, in the county of Milwaukee and State of Wisconsin, have invented a new, original, and ornamental Design for a Rolling-Pin, of which the following is a specification, reference being had to the accompanying drawing, forming part thereof.

In the drawings:—

Figure 1 is a top plan view of the device and Fig. 2 is a front elevation of the same, showing my new design.

I claim:—

The ornamental design for a rolling pin, as shown.

STANISLAW KIELAR.

Witnesses:

F. X. SWIETLIK,
EMMA WEGENER.
